TAG PRINTING MACHINE

Edward W. Flood and Carl A. Flood, Framingham, Mass., assignors to Dennison Manufacturing Company, Framingham, Mass., a corporation of Massachusetts

Application October 10, 1942, Serial No. 461,564

4 Claims. (Cl. 101—288)

1

This invention relates to an improvement in the art of pin ticketing material, and more particularly in a machine by which tags are prepared as by printing and thereafter attached by pins to the material.

The patents to Carl A. Flood, No. 2,083,150, granted June 8, 1937, and No. 2,136,941, granted November 15, 1938, each discloses machines of this general type wherein tags are fed in a strip to a predetermined location at which the tags are printed, severed from the strip, and fed individually to a point at which they are attached to a material by the use of pins supplied at that point. The present invention is an improvement upon these patented machines, and has as its primary object to provide a tag printing machine in which a plurality of longitudinally extending zones of the tag can receive the same impression of printing from the same printing type, by appropriate relative movement between the printing head and the tag, the head acting to print successively in the various relative positions of the head and tag.

A further object is to provide an improved operation of a shiftable tag-carrying platen to bring about the relative movement between the printing head and platen in the successive printings of the several longitudinally extending zones of the tag carried thereby.

A further object is to provide controlling means for selectively determining the number of relative shifts between printing head and tag and the number of printings per tag.

Another object is to provide for rendering ineffective the means for causing relative shift between the printing head and tag and for limiting the action of the printing means to one printing per tag, when desired.

As is well known in the art of stock control and price marking, it is often desirable for price tags to carry the same printed matter repeated one or more times on the same tag, so that in the course of business the tag can be cut or torn apart into several printed portions each used for a different purpose in store accounting. It is also desirable when tags are pinned or otherwise fastened to merchandise to fasten the tag by a pin, staple, or other fastener that extends laterally across the top of the tag. With the tag so fastened it is desirable that each occurrence

2

of the text that is reproduced several times on the tag shall occupy a separate longitudinally extending zone on the tag, i. e. a separate zone extending up and down on the tag, each such zone that carries the identical text lying side by side.

For a number of years it has been recognized that this arrangement of the zones carrying the several copies of the text is desirable in order that the free end of the tag opposite to the end that is pinned or otherwise fastened to the merchandise, may include the end portions of each of the several such zones. Then in re-marking or otherwise changing the text of the tag while on the merchandise, each one of the several zones of the tag has a readily accessible end portion distant from the pin or fastener to receive a further mark or have a part thereof cut off, or both, all without interference with the pin or the fastener. However, it is undesirable to have to set up or arrange separate type or separate sets of printing elements to print in the respective longitudinal zones because there is danger of error and failure to set up the identical text in the separate sets of type.

The present invention is particularly applicable to the printing of tags such as just described, and has the advantage of enabling such tags with longitudinally extending zones of printing to be printed by a single set of type set up to print the text which is to be repeated in the several longitudinally extending zones of the tag. This use of a single set of type to make the repeated impressions on the tag is advantageous in assuring absolute uniformity in the text in the several zones of the tag.

These and other objects of the invention will appear from a consideration of this specification and its drawings wherein the invention is explained by way of example.

40 In the drawings:

Fig. 1 is a front elevation of a machine embodying this invention;

Fig. 2 is a left elevation of the machine with portions broken away;

Fig. 3 is a partial right elevation of the machine taken on a larger scale and disclosing only the forward portion thereof;

Fig. 4 is a plan view of the table of the machine;

Fig. 5 is a view of the mechanism by which the tags are severed and printed, looking from front to rear, and with parts broken away and omitted;

Fig. 6 is a similar view showing the printing mechanism;

Fig. 7 is a similar view showing the platen moving mechanism;

Fig. 8 is a left-hand view of the mechanism shown in Fig. 7, taken along the line 8-8;

Fig. 9 is a plan view on a reduced scale illustrating the relation of the tag strip and the pin strip as they are fed to the table;

Fig. 10 is a vertical sectional view taken along the line 10-10 of Fig. 4, but on a larger scale, showing the tag feeding guideway with a wide tag therein;

Fig. 11 is a view similar to Fig. 10 showing a narrower tag in the guideway;

Figs. 12, 13 and 14, inclusive, illustrate the various positions taken by a tag in which three separate printing impressions are applied thereto;

Fig. 15 illustrates the completed tag as it is being advanced from the platen;

Fig. 16 illustrates the tag when the first of three impressions is being applied thereto and while the severing of the tag from the strip is taking place; and

Fig. 17 is a chart illustrating diagrammatically the relative timing of the mechanical movements controlled by the various cams.

The machine 20, illustrated in the drawings as one embodiment of the invention, is adapted to print tags T (Figs. 12 to 15) with one, two or three identical longitudinally extending zones, each carrying data as to the selling price, cost, style, source, etc. of the material to which the tag is to be attached by the machine. Since, when only one or two such zones are to be printed on the tag, a tag approximately two-thirds of the width of that shown in Figs. 12, 13, 14 and 15 will be sufficient, the machine is provided with means by which such a tag can be handled.

The machine 20 includes a base 21, a front wall 22, portions of which are cut away, and a table 23 upon which the work is performed, as will be described herein. Detachable walls which further enclose the space between the base and table have been omitted in the drawings for the purpose of clarity.

The main shaft 25 by which the various instrumentalities are actuated is supported at its forward end in the front wall 22 and near its rear end in a casing 26. This shaft is driven by a motor through suitable gearing here shown as including a worm 28 and worm gear 29, shown in dotted lines in Fig. 2, and manually controlled clutch mechanism. The shaft and gears are enclosed within the casing 26 which also serves as one of the supports for the table 23. The clutch mechanism shown is of the type described in detail in the patent to Flood No. 2,083,150, and includes a disk 30 fixed to the shaft 25, a finger 31 which prevents movement of the disk in one direction, a pawl 32 on disk 30 which engages a ratchet wheel (not shown) driven by the worm gear 29 and a movable block 33 which in one position (Fig. 2) engages the pawl 32, disconnects the pawl from its ratchet wheel, and prevents rotation of disk 30 and the shaft 25. The block 33 is mounted at one end of a rod 34 which extends below the table 23 through the front wall 22 and carries plate 35 adapted to be pushed in by the thumb or finger of the operator to set the machine in operation. Suitable spring means

(not shown) are provided to hold the block 33 normally in engagement with the pawl 32.

Preferably, as shown in the drawings, the machine may be supplied with strips of tags T of the character disclosed in the patent to Flood No. 2,136,941, which are formed of two laminae as by folding the sheet back upon itself and securing the folded portions together and in which the outer face is supplied near the fold line with a plurality of equally spaced holes which are engaged by the feeding means to advance the strip a plurality of predetermined distances.

The tags T are supplied from a magazine 40 mounted upon the table 23 and are cut from a strip S formed in a coil which is rotatably supported upon a stud 41 within the magazine. The stud 41 is fixed rigidly on a cross-plate 42 and projects from both faces thereof parallel to the table 23. The coil on the stud 41 is between vertical straps 43 and 44. The strap 43 is mounted on the cross-plate 42 and terminates at each end in flanges 45 which project toward the strap 44. The strap 44 is mounted on the stud 41 and has a central bayonet type opening 46 adapted to enter one of the two annular grooves 47 in the stud 41. If the strip is of the width to make tags for three columns of data in three longitudinally extending zones, as shown in Fig. 1, the strap 44 engages the outer groove 47, and if the strip is of the width to make tags for two columns of data, in two longitudinally extending zones, the strap engages the inner groove 47. The strip S is guided between curved plates 48 and 49 (Figs. 2 and 4) into a guideway 50 (Fig. 4) along which it is fed.

The tag feeding means here shown is described in detail in the Flood Patent No. 2,083,150. Such means comprises briefly a pair of pivotally mounted bell crank levers 51 and 52 (Fig. 2) actuated by cams 53 and 54 on the shaft 25, with which cams they are held in contact by springs 55, a feeding finger 56 (Fig. 4) pivoted on the lever 51, and a pusher 57 pivoted on the lever 52 and yieldably held in contact with the tag strip. Feeding finger 56 and pusher 57 are yieldingly held downwardly by coil springs 56a and 57a respectively.

The inner wall of the guideway 50 is formed by an inverted U-shaped guide bar 58 pivotally mounted on brackets 59 (Figs. 4, 10 and 11). In the base plate 60 of the guideway 50 is formed a longitudinally extending groove 61 (Figs. 10 and 11) near the inner edge of the base plate. When the tag strip S is of the width to receive three columns of identical data, the strip passes under the outer wall 62 of the guide bar 58 and is guided by the inner wall 62a of the guide bar 58, as shown in Fig. 10. If, however, the strip S is narrower so as to receive two columns only of identical data, the strip is guided by the outer wall 62 which then rests in the groove 61, as shown in Fig. 11.

Occasions arise, as for example a change in strips, when it is desired to suspend the feed of the strip while continuing the operation of the other elements of the machine. A plate 63 normally held by a set screw 64 in the position shown in Fig. 4 can, thereupon, be advanced in the guideway 50 below the feeding tip of the finger 56 far enough so that, although the finger is free to reciprocate, it cannot engage the holes in the tag strip. Moreover, if tags half the length of those shown in Figs. 12 to 16, inclusive, are desired, the plate 63 will be advanced to such an extent that while the feeding finger 56 travels

idly thereon during the first half of its movement, it is free to engage the tag during the second half of its movement with the result that the forward travel of the strip is reduced accordingly.

In the preferred form of the invention herein shown, the leading end of the strip S passes from the guideway onto a platen 65 which comprises a base 66 on which the tag rests during the printing operation, and a pair of undercut margin strips 67 and 68. At the end of the guideway 50 is mounted a vertical cross-plate 69 which is spaced above the guideway so that the strip passes freely thereunder and which is notched in its lower edge to permit travel of the pusher 57 thereunder (see Fig. 5). After the leading end of the strip S has traveled a predetermined distance onto the platen 65, the portion thereon is severed from the strip by a cutting knife 70. The knife 70 moves in a plane at right angles to the guideway and is rigidly secured to the upper arm of a bell crank lever 71 (Fig. 4) rockable about a stud shaft 72 and having on its other arm a roller 73 (Fig. 3) which is yieldably held in contact with a cam 74 on the shaft 25 by a spring 75.

The base plate 66 of the platen 65 is rigidly mounted upon a plate 80 (Figs. 4 and 7) mounted for reciprocation over the table 23 between guides 81 at right angles to the strip guideway 50. The outer margin strip 67 is rigidly secured to the base plate 66 of the platen 65. The inner margin strip 68, however, is adjustable so that the platen will receive tags T of two different widths. Projecting inwardly from the strip 68 is an arm 82 (Figs. 4 and 7) which terminates in a flange 83 (Fig. 7) projecting downwardly past the inner edge of the base plate 66. Carried by the arm 82 is a manually adjustable rod 84 which passes freely through openings in posts 85 and 86 mounted on the plate 80. A spring plate 87 carried by the post 86 bears against the rod 84 and frictionally resists its movement. When the wider tag T is in use, the inner margin strip 68 is set as shown in the drawings (Fig. 7), with the arm 82 and flange 83 abutting the post 85, and when a narrower tag is used, the strip 68 is set with the flange 83 in contact with the inner edge of the base plate 66.

The platen 65 supports the tag while the columns of data are applied thereto as by a printing head 90 which may be of any desired construction, and which preferably is in the form of a chase adapted to receive and hold several lines of changeable type 91 capable, if desired, of being set up to print a column consisting of several lines one under the other. The impression made by this set of type is ordinarily to be repeated in each of the number of longitudinally extending zones of the tag.

Preferably the chase of the printing head has a capacity large enough so that when desired it may hold a group of type of an area which will substantially fill up a tag, or the major part of a tag at one impression. Ordinarily, however, a lesser width of the chase will be used to hold type, and the area of the type will be such as can print on one of the several longitudinally-extending zones of a tag, and then to print in the one or more other such zones of the same tag. The head 90 (see Fig. 6), which includes a ribbon 92 by which the type is provided with ink, is mounted on a plate 93 (Figs. 5 and 6) vertically reciprocable in a cage 94 supported by the table 23. The printing head 90 is reciprocated by a bell crank lever 95 through a link 96 which connects the plate 93 to one arm of the lever 95.

The lever 95 is mounted to rock about the stud shaft 72 which also supports the knife lever 71. The other arm of the lever 95 is connected by bolts 96 and 97 to one arm of a bell crank lever 100 also mounted to rock about the stud shaft 72. The bolt 96 limits positively any movement of separation of the levers 95 and 100 while the bolt 97 acts through a spring 98 and nut 99 (see Fig. 5) to hold the levers yieldably at the relation set by the bolt 96. Thus, these bolts permit adjustment of the amount of pressure exerted by the head 90 upon the tag. The lever 100 terminates at its other end in a yoke 101 which supports a pin 102 on which a roller 103 turns freely. As pointed out above, the printing head 90 applies one, two or three impressions upon the tag in the platen 65. These three operations are imparted to the head by cams 105, 106 and 107 (Fig. 6) mounted on the shaft 25. The roller 103 is brought selectively into position to be contacted by either cam 105 alone, or by cams 105 and 106, or by all three cams 105, 106 and 107 depending upon the number of impressions per tag, by means of a shifter bar 108 (Figs. 3, 5 and 6) pivotally mounted on the lever 100 by a pin 109 carried by a boss 110. The lower end of the shifter bar terminates in a yoke 111 which spans the roller 103 and is so formed that its legs are adapted to bear against the side walls of the roller (see Fig. 3). At the upper end of the shifter bar 108 is mounted a stud 112 which is adapted to engage selectively any one of three depressions 113 (Fig. 3) arranged arcuately in a plate 114 carried by the lever 100. A spring 115 (Fig. 6) connected at one end to the lever 100 and at the other end to a post 116 depending from the table 23 holds the roller 103 yieldably in contact with the selected cam or group of cams. Figs. 3 and 5 show the machine set so that only a single column is printed on each tag, the roller 103 being set for engagement with only the cam 105, and Fig. 6 shows the machine set so that three columns are printed on each tag.

The movement of the platen 65 depends upon the number of impressions applied by the printing head 90. If only a single column is to be printed, the platen remains stationary and the printed tag is at the proper time pushed out of the platen. If two columns are to be printed, the platen is shifted first to the right where the left one of the two columns is printed, then to the original position, i. e. that at which the tag is received, for the printing of the other of the two columns and the discharge of the tag. If three columns are to be printed, the middle column (Figs. 12 and 16) is printed with the platen in its original position, this printing taking place near the end of a rotation of the main shaft 25. The platen is then shifted to the right during the next rotation of the main shaft to receive the second or left impression (Fig. 13), then the platen, after printing of the second column, is shifted to the left so that the third column is applied at the right of the initial column (Fig. 14) and finally returned to the original position at which the tag is discharged (Fig. 15).

The shifting movement is imparted to the platen by a lever 120 pinned or otherwise attached to a rock shaft 121 supported in journals on the base 21. The lever 120 is connected by a link 122 to a tab 123 depending from the plate 80 through a slot 124 (Fig. 8) in the table 23. Integral with or rigidly secured to the lever 120 is a bar 125 (Fig. 8) which extends parallel to the rock shaft 121 and carries at its outer end a stud

or pin 126. Mounted to rock freely on the rock shaft 121 and shiftable therewith is a lever 127. The lever 127 is provided with three suitably spaced holes or depressions 128 each adapted to receive the pin or stud 126. Rotatably mounted in a slot 129 at the outer end of the other arm of the lever 127 is a roller 130 adapted to mesh selectively with any one of three cams 131, 132 and 133 mounted upon the main shaft 25. The depressions 128 are so arranged that, when the lever 127 is shifted so that the stud 126 is seated in a selected depression, the roller 130 will bear against the cam associated with that depression (see Fig. 8). A spring 134 attached at one end to a stud 135 carried by the table 23 and at the other end to the tab 123 yieldably holds the roller 130 in contact with the selected cam. In order to shift the roller 130 and bring it into engagement with a desired cam, the plate 80 is drawn to its advanced position, i. e. to the left in Fig. 7, against the urge of the spring 134, and the lever 120 is thus moved positively in the counterclockwise direction (Fig. 7). When the lever 120 is so moved, the lever 127 is free to be rocked on the shaft 121 to disengage the stud 126 from the depression 128 in which it is seated so that the lever 127 can be slid longitudinally along the shaft 121 until the desired depression is brought into register with the stud. The lever 120 is now released so that the roller 130 will bear against the selected cam. A button 136 (Fig. 4) on the table 80 and a knob 137 on the lever 127 (Figs. 5, 7 and 8) facilitate this selection of the cam by which the movement of the platen is controlled. In the illustrated machine, the cam 131 is provided with three peripheral levels or dwells, the cam 132 is provided with two peripheral levels or dwells, and the periphery of the cam 133 is circular and concentric (see Fig. 7). Thus, the machine, as shown in Figs. 7 and 8, is set with the roller 130 bearing against the cam 131 to impart three shifts of the platen so that three columns of data will be printed on the tag.

After the printing of the tag is finished, the pusher 57 advances into engagement with the rear edge of the tag, removing it from the platen 65 into the range of the unit by which the tag is pinned to the material for which it has been prepared. The unit illustrated in the drawings is substantially that disclosed in the above-mentioned patent to Carl A. Flood No. 2,083,150, and will be only briefly described herein.

The tag T leaving the platen 65 is supported over a vertically reciprocable anvil 140 by a shelf 141 upon which one side edge of the tag rests (Fig. 1). If the tag be of the width to receive three columns of data, the other edge bears against a flange 142 projecting downwardly from a rigidly mounted plate 143, and if the tag be of the narrower width, the other side edge bears against the side face of the plate 143.

The anvil 140 on which the material to receive the tag is placed is reciprocated by mechanism comprising a double-faced cam 144 mounted on the main shaft 25 having a cam track 145 on one face, a lever 146 pivoted on a rock shaft 147, a second lever 148 pivoted to the lever 146 and interconnected at one end with the anvil 140, and a tension spring 149 by which the outer ends of the levers 146 and 148 are connected.

The pins by which the tags are attached to the material are removably carried by a paper strip mounted in the hood 40 in the form of a coil 151. The coil 151 is supported upon one end of the stud 41, which end is separated by the cross-plate 42 from the end which supports the tag strip 8, and

is held in position thereon by a strap 152 which engages the stud in the same manner as does the strap 44 for the tag strip. The strip 150 passes from the hood 40 through a guiding trough 153, down a vertical passageway 154 to a slot 155. The pins are removed from the pin strip as it enters the slot 155 and the strip passes to the right of the machine between intermittently driven rollers 156, 157 by which the strip is advanced (Fig. 3).

10 The pin is removed from a strip and passed through the material and tag on the anvil 140 by a plunger 160 carried by a driver head 161.

The driver head 161 is actuated by the cam 144 through a cam track (not shown) on the face opposite the face carrying the cam track 145. The cam 144 reciprocates a bell crank lever 162 (Figs. 1 and 3) pivoted on the rock shaft 147, and an arm 163 (Fig. 3) yieldably connected to the lever 162 and pivotally connected at its lower end to the rock shaft 147 and at its upper end to the driver head 161. The pin strip advancing rollers 156, 157 are actuated by a pawl 165 (Fig. 3) on the driver head 161 which engages a ratchet 166 on the roller 157 to advance the strip 150 one step after each pin has been removed therefrom.

25 The various cams on the main shaft 25 are mounted in such a manner that the various operations described above take place in definite order. Fig. 17 illustrates diametrically the operations of these cams during the rotation of the shaft through one complete cycle, and shows the timing of such operations. The curve A represents the movement of the strip feed finger 58, curves B, C and D represent the movements of the printing head 60 during the application of one, two or three impressions, respectively, upon the tag T, curves E, F and G represent the movements of the platen 65 during the same conditions, curve H represents the movement of the pusher 57 by which the tag T is removed from the platen 65, curve I represents the movement of the cutter 70, and curve J represents the movement of the pin inserting plunger 160.

Curve A shows that the feeding finger 58 remains stationary during the first half of the cycle and during the second half advances to feed the forward end of the strip onto the platen and at the completion of the cycle then resumes its normal position.

50 Curves B, C, D, E, F and G will be considered in pairs since they relate to three different and independent settings of the machine.

Curves B and E apply when a single impression is applied upon the tag T. The printing head 60 begins its approach shortly before the first quarter of the cycle has been completed, and resumes its normal station just before the second quarter has been completed and is stationary during the rest of the cycle (curve B), while the platen 65 remains stationary throughout the entire cycle (curve E).

Curves C and F apply when two impressions are applied. The printing head 60 starts its descent for the first impression with the beginning of the cycle, completes that impression with the first quarter, immediately starts its descent for the second impression which it completes with the second quarter, and remains at rest during the completion of the cycle (curve C) while the platen 65 is shifted to the right-hand position and held therein during the first impression so that the first column printed is the one adjacent the left edge of the tag, returns to normal as the printing head starts its descent for the second

impression, and remains stationary to the end of the cycle (curve F).

Curves D and G apply when three impressions are applied. The printing head 60 applies the last two impressions to a tag during the same period within which the two impressions are applied when the machine is set for two-impression operation (see curve C). The other impression (in the middle column) is received during the last portion of the preceding cycle (curve D). The platen 65, carrying the tag which has its middle column already printed, is shifted first to the right-hand position so that the tag receives an impression adjacent its left edge, second to the left-hand position so that the tag receives an impression adjacent its right edge, and third to its normal position. In this three-impression operation, the impression that is then applied when the platen is in normal position is received by the next tag of the sequence, the operations of the tag pusher 51 and strip feed finger 56 (curves A and H) having taken place before this impression.

From the above it will be noted that one impression of each setting is applied while the platen 65 is at rest in its normal position (corresponding to Fig. 12), that in the two settings where more than one impression is applied, another impression is applied while the platen is in its right-hand position (corresponding to Fig. 13), and that in the setting where the three impressions are applied, the third impression occurs while the platen is in its left-hand position. This left-hand position of the platen (corresponding to Fig. 14) is not used when either one or two impressions are made per tag, and the right-hand position of the platen (corresponding to Fig. 13) is not used when only a single impression is made per tag.

Curve H shows that the pusher 51 remains stationary behind the cutter 70 (see Fig. 4) until near the end of the first half of the cycle and then advances to push the printed tag T out of the platen. It will be noted that in each setting of the machine the effective portion of the advance of the pusher 51 takes place while the platen 65 is stationary in its normal position, and that the pusher 51 precedes the feeding finger 56 so that the printed tags do not impede the feed of the strip.

Curve I shows that the cutting of the tag from the strip occurs in the last quarter of the cycle and that the cutter completes its return to its normal position at the start of the cycle. In each setting of the machine the platen 65 is stationary during the cutting operation.

Curve J shows that the pin driver 160, by which the pin is driven through the material and tag, operates near the end of the cycle and substantially in unison with the cutter 70, and that the final rearward movement of the driver head by which the pin strip is advanced takes place at the beginning of the cycle.

We claim:

1. A tag printing machine comprising periodically operating means for advancing the tag lengthwise, a type-carrying printing head arranged to print on a longitudinally extending zone of the tag, means, acting between successive operations of the lengthwise advancing means, for causing between such operations a cycle of back and forth shifting movement of the relative positions of the printing head and tag transversely of the path of advance to relative positions of the printing head and tag in which different longitudinally extending zones of

the same tag are presented to the same type of said printing head, and means for operating the printing head a plurality of times for each said cycle of transverse relative shifting movement between successive operations of the lengthwise advancing means, at times when the respective different longitudinally extending zones of the tag are presented to said same type.

2. A tag printing machine comprising periodically operating means for advancing the tag lengthwise, a platen, a type-carrying printing head arranged to print on a longitudinally extending zone of a tag on the platen, means, acting between successive operations of the lengthwise advancing means, for causing between such operations a cycle of back and forth shifting movement of the relative positions of the printing head and platen transversely of the path of advance to relative positions of the printing head and platen in which the platen presents different longitudinally extending zones of the same tag to the same type of said printing head, and means for operating the printing head a plurality of times for each said cycle of transverse relative shifting movement between successive operations of the lengthwise advancing means, at times when the platen presents the respective different longitudinally extending zones of the same tag to said same type.

3. A tag printing machine comprising periodically operating means for advancing the tag lengthwise, a platen movable into and out of longitudinal alignment with the path of advance, a type-carrying printing head arranged to print on a longitudinally extending zone of a tag on the platen, means, acting between successive operations of the lengthwise advancing means for causing between such operations a cycle of back and forth shifting movement of the platen transversely of the path of advance to positions in which the platen presents respectively different longitudinally extending zones of the same tag to the same type of said printing head, said cycle of shifting movement of the platen beginning and ending with the platen in longitudinal alignment with the path of longitudinal advance, said platen when in longitudinal alignment with the path of advance being adapted to receive a tag and to discharge the preceding tag, and means for operating the printing head a plurality of times for each said cycle of transverse shifting movement of the platen between successive operations of the lengthwise advancing means, at times when the platen presents the respective different longitudinally extending zones of the same tag to said same type.

4. A tag printing machine comprising periodically operating means for advancing the tag lengthwise, a platen movable into and out of longitudinal alignment with the path of advance, a type-carrying printing head arranged to print on a longitudinally extending zone of a tag on the platen, means, acting between successive operations of the lengthwise advancing means for causing between such operations a cycle of back and forth shifting movement of the platen transversely of the path of advance to positions in which the platen presents respectively different longitudinally extending zones of the same tag to the same type of said printing head, said cycle of shifting movement of the platen beginning and ending with the platen in longitudinal alignment with the path of longitudinal advance, means for selectively determining the number of said positions to which the platen brings the tag

during its cycle of back and forth shifting movement, said platen when in longitudinal alignment with the path of feed being adapted to receive a tag and to discharge the preceding tag, and means for operating the printing head a plurality of times for each said cycle of transverse shifting movement of the platen between successive operations of the lengthwise advancing means, at times when the platen presents the respective different longitudinally extending 10 zones of the same tag to said same type.
